UNITED STATES PATENT OFFICE.

JARVIS B. EDSON, OF ADAMS, MASSACHUSETTS.

APPARATUS FOR POLISHING SHEETS OF ZYLONITE, &c.

SPECIFICATION forming part of Letters Patent No. 289,239, dated November 27, 1883.

Application filed April 28, 1883. (No model.)

To all whom it may concern:

Be it known that I, JARVIS B. EDSON, of the town of Adams, in the county of Berkshire and State of Massachusetts, have invented new and useful Improvements in Apparatus for Polishing Sheets of Zylonite or similar Substances, of which the following is a specification.

This invention has for its object the polishing or finishing in a very smooth condition the surface of sheets of zylonite or similar compounds chiefly formed of pyroxylene or cellulose substances; and the invention consists in slightly dissolving the surface of the sheet by some solvent—as collodion, or any of the well-known solvents of such substances—and then subjecting the said surface to pressure in contact with a highly-polished surface—as a plate of glass—which, as the pressure advances, gradually expels the air and closely compresses the surface of this partially-dissolved surface and sets it in a closely-finished condition, until it is as highly polished as the glass or finishing surface with which it has been in contact while under pressure.

In the drawings at Figure 1 is represented a section of a pair of pressure-rolls, between which are represented a sheet of the material to be polished and the polishing-plate. At Fig. 2 is a similar transverse section of the rolls, but with the polishing-surface made in any cylindrical form, so as to be continuous in its operation instead of intermittent, as in the other figure.

At A B are represented a pair of rolls, one or both of which may be of rubber or some elastic substance, so that a plate of glass may be passed between them without fracture.

At C is represented a sheet of the zylonite or similar substance, which may be fed from a roll, as at D; and at E is a distributing device, which may be a roller, as represented; or it may be a tube with jets to distribute some solvent—as collodion—upon the surface of the sheet of zylonite, and immediately before its contact with the polishing-plate F, which is preferably a plate of glass, as at present it seems to be the best material which I have found for the purpose, and which, when passed between a pair of rolls in contact with the said partially-dissolved surface of the sheet of zylonite, has

the effect, as the pressure advances, of expelling the air from the composition, and at the same time so compress and finish the surface as to make it as smooth as the glass with which it has been in contact.

At Fig. 2 the same relation of devices is used, except that instead of a plate of glass a cylinder of glass, as at G, is mounted between the rolls, so that the operation may be performed continuously, as would be required where long sheets of the zylonite were formed as in a web.

It is evident that if figures of designs of any kind be formed either on the plate or cylinder of glass, as by the process of engraving or etching, corresponding figures will also be formed on the surface of the zylonite sheet, so that any desired ornamentation may be produced at the same time that the surface is being finished or polished.

It is evident that vitrified surfaces mounted upon plates of metal may be used in place of the plate F or cylinder G, and it may be possible by some process, as by electroplating or in some other manner, to finish plates of metal so that their surfaces may be as highly polished as plates of glass, in which case they could be used in the same manner; but the essence of the invention consists in compressing the partially-dissolved surface of a sheet of zylonite or a similar substance in contact with a highly-polished surface, for the purpose of expelling the air and so compressing the surface as to give it a highly finished or polished condition.

From the foregoing it will be perceived that my invention differs from that contained in Patent No. 221,070, which is hereby disclaimed.

I therefore claim—

1. The within-described process of polishing sheets of zylonite or similar substances by first slightly dissolving their surfaces by any of the well-known solvents for such purpose, and then subjecting the same to pressure, with the slightly-dissolved surface in contact with the surface of a highly-polished substance—such as glass—in the manner set forth, and for the purpose specified.

2. The combination of a pair of compressing-rolls adapted for receiving a sheet of zylonite or similar substance, a distributing device

for applying the solvent, and a polishing-plate, as hereinbefore set forth.

3. The combination of the pressure-rolls and a polishing-cylinder interposed between the same, for the purpose of forming a continuously-polished surface upon a plastic substance, as hereinbefore set forth.

In witness whereof I have hereunto subscribed my name and affixed my seal in the presence of two subscribing witnesses.

JARVIS B. EDSON. [I. S.]
